DESIGN FOR A SPOON OR OTHER ARTICLE OF FLATWARE

George A. Feinauer, Providence, R. I., assignor
to Gorham Manufacturing Company, Providence,
R. I., a corporation of Rhode Island

Application January 30, 1936, Serial No. 60,895

Term of patent 14 years

To all whom it may concern:

Be it known that I, George A. Feinauer, a citizen of the United States of America, of 227 Gallatin Street, Providence, Rhode Island, have invented a new, original, and ornamental Design for a Spoon or Other Article of Flatware, of which the following is a specification, reference being had to the accompanying drawing forming part thereof.

Figure 1 is the obverse side of a spoon showing my new design, while Figure 2 shows the reverse side of the same spoon. Figure 3 is a cross-section of Figure 1 on line 3—3. Figure 4 is another cross-section on line 4—4 of Figure 1.

I claim:

The ornamental design for a spoon or other article of flatware substantially as shown.

GEORGE A. FEINAUER.
